(57) **CLAIM**

The ornamental design for an automobile headlight, as shown and described.

DESCRIPTION

FIG. 1 is a perspective view of an automobile headlight; FIG. 2 is a front view thereof;

FIG. 3 is a side view thereof; and,

FIG. 4 is a top view thereof.

The broken lines in the drawings depict portions of the article that form no part of the claimed design.

The drawings and descriptions represent the left-side embodiment. The claim is also for a mirror image right side embodiment.
